INVENTOR
Samel Rappaport

BY *Lester D. Leventhal*

ATTORNEY

UNITED STATES PATENT OFFICE.

SAMUEL RAPPAPORT, OF BROOKLYN, NEW YORK.

HAT RECEPTACLE.

Application filed April 10, 1923. Serial No. 631,070.

To all whom it may concern:

Be it known that I, SAMUEL RAPPAPORT, residing at the city of New York, borough of Brooklyn, in the county of Kings and State of New York, have invented certain new and useful Improvements in Hat Receptacles, of which the following is a specification.

This invention relates to a hat box or case provided with an improved holder for retaining a hat within the receptacle.

Hat boxes or cases as now constructed are generally provided with a support over which the crown of the hat is placed. In the ordinary cardboard box commonly used for delivering or shipping individual hats the support consists of a cardboard cylinder. With such boxes or cases the hat is held in place by means of strings tied over the brim or crown, or by pinning the hat to the support. As the support may be smaller in diameter than the crown, there is a possibility that the hat will shift within the container. Furthermore, particularly in the case of women's hats made of fine fabrics and ornamented with delicate trimmings there is a danger that the fastening means will damage or injure the hat either when tied in the box or pinned to the support.

One of the objects of my invention is to provide an expansible holder which functions to retain a hat by frictional engagement with the interior of the crown.

A further object is to provide a holder that is self-adjusting to various hat-sizes.

With these and other objects in view, my invention comprises the novel features of construction hereinafter described, it being understood that various modifications may be made therein without departing from the scope of the claims.

In the accompanying drawings, illustrating a preferred embodiment;

Figure 1 is a plan view of a hat box, with the cover removed; and

Figure 2 is a sectional elevation, on the line 2—2 of Fig. 1, with the cover in place.

Referring to the drawings, 1 indicates a support preferably, though not necessarily, made of a single piece of suitable resilient

material curved in the direction of its length to form a coil or spiral and thereby providing an expansible or elastic hat-holder. I have found in practise that cardboard of a springy character may be used satisfactorily and economically to make the holder. 55

The support is secured through part of its length to one wall of the receptacle, leaving the outer end portion free of attachment that it may function as an expanding or elastic holder. In the present instance, the support 1 is provided at spaced intervals with tabs 2 by means of which it may be fastened, either permanently or detachably, to the bottom 3 of the hat-box 4, as seen 65 in Fig. 1.

The hat box 4 shown in the drawings is of cylindrical shape, partly flattened to provide a rest when the box is stood on its side. While I prefer to employ a box of 70 this character, it is to be understood that I do not limit my invention to boxes or cases of any particular shape or style.

The manner in which the invention operates is as follows: The loose end of the 75 support or holder is wound around the fixed portion, and the hat is then placed in the box its crown positioned over the support. The loose end of the holder will now expand, automatically adjusting itself to the 80 diameter of the crown, and by frictional engagement with the interior of the crown will firmly hold the hat in place against dislodgment through any ordinary shock.

What I claim is:

1. In a hat receptacle, means for retaining a hat comprising a spirally shaped support of spring cardboard secured through part of its length to an interior wall of the receptacle and having its outer end portion free. 85

2. In a hat receptacle, means for retaining a hat comprising a spirally shaped support of springy cardboard having tabs at spaced intervals through a portion of its length, said tabs being fastened to the inside of the bottom of the receptacle, and having the outer end portion of the support free 95 from attachment to the receptacle.

SAMUEL RAPPAPORT.
